UNITED STATES PATENT OFFICE.

CHARLES H. MERRITT, OF BELLINGHAM, WASHINGTON.

STRINGED MUSICAL INSTRUMENT.

Application filed October 9, 1926. Serial No. 140,471.

My invention relates to an improvement in stringed musical instruments, particularly instruments of the type of the banjo, wherein strings are stretched between a head and a neck extending therefrom.

One of the objects of this invention is to apply the vibrations of the strings, which are ordinarily absorbed in the rigid neck, through the neck to the head or drum in such a way that the amplitude of vibration of the head is increased and the sound persists in the head, to the end that the instrument, ordinarily but slightly resonant, is made more resonant, and its tonal qualities are improved.

Another object is the arrangement of parts of such an instrument in such a way that the head is acted upon from opposite sides so that the vibratory effect from each side is, to a certain extent, counteracted and amplified by the effect from the opposite side.

Other objects of my invention will become apparent as the description progresses.

My invention comprises the novel parts and arrangement of these parts and other, standard, parts, relative to each other to produce the effects described above.

In the accompanying drawings I have shown my invention in association with a banjo, though it will be understood that the principles thereof may be applied equally as well to other types of stringed instruments, such as the mandolin, guitar and ukulele, which employ a projecting neck.

Figure 1 is a general side elevation of my invention, the banjo head and rim being shown in section.

Figures 2, 3 and 4 are sections on the respective lines 2-2, 3-3, and 4-4 of Figure 1.

Ordinarily the neck 3 of a banjo or like instrument, which carries the nut 30, forming the outer support for the strings 4, is rigidly connected to a head formed of the rim 2 and the membrane 1. The inner end of the strings 4 is secured in some suitable tail piece, as indicated at 5, and the vibration of these strings is transmitted to the membrane 1 through a bridge 6, interposed between the head and the strings. Thus the tension of the strings 4 presses the bridge against the head, and the vibration of the strings is only transmitted to the head in the one direction and at the one point. The strings vibrate as much at the nut 30 as at the bridge 6, but the vibration at the nut 30 is absorbed in the neck 3.

According to my invention, the neck 3, and the extension 31 thereof, which ordinarily forms the dowel post rigidly spacing opposite sides of the rim 2, is pivoted upon a transverse pivot 32, supported in brackets 23 secured upon the rim 2. Thus the entire neck 3, 31 is free to oscillate upon the pivot 32 in accordance with the vibrations transmitted to it at the nut 30.

I now provide means for transmitting to the one side of the head 1 such vibrations, and the particular mechanism to effect this result may be any which is found suitable. As shown herein, a short lever 7 is pivoted at 72 upon brackets 27, secured upon the inner periphery of the rim 2. One end of this lever 7 is connected by links 71 to the end of the extension 31 of the neck, the pin 73 connecting these members. Movement of the short lever 7, which is caused to vibrate with the neck 3 by the connection described, is in turn communicated to the inside or under side of the head 1 by suitable means, such as the bridge or knife-edge contact member 60, which, in effect, forms part of the lever, 80 though usually not secured thereto. Thus the tension of the strings 4, acting through the neck 3, causes a pressure at 60 upon the head 1 in opposition to the bridge 6, and these pressures may be made nearly equal in amount. Preferably, however, the points of contact are spaced, as contact at the same points has a tendency to mute the instrument.

I have found, with an arrangement as described, that is, through the provision of means whereby vibration of a free neck is transmitted to the underside of the head, that the resonance of the instrument and its sweetness of tone is markedly and pleasingly increased, and the volume is likewise increased to a considerable extent.

What I claim as my invention is:

1. The combination, in a stringed musical instrument, of a head comprising a rim and a membrane, a neck supported between its ends in said head for free vibration relative thereto, vibratory strings, a nut on the outer end of said neck forming a bearing for one end of said strings, their other end being secured to said rim, a bridge interposed between said strings and said membrane, and means operatively connected with said pivoted neck for transmitting its vibrations to the membrane.

2. The combination, in a banjo or like

- stringed musical instrument, of a rim, a membrane supported thereon, a neck projecting from the rim, strings stretched from the outer end of said neck to a point of securing on said rim opposite said neck, a bridge interposed between said strings and the membrane, means pivotally supporting said neck, intermediate its ends, from the rim for free vibration relative thereto, and means for transmitting the vibrations of said neck to said membrane.
3. The combination, in a banjo or like stringed musical instrument, of a rim, a membrane supported thereon, a neck projecting from the rim, strings stretched from the outer end of said neck to a point of securing on said rim opposite said neck, a bridge interposed between said strings and the membrane, means pivotally supporting said neck, intermediate its ends, from the rim for free vibration relative thereto, and means for transmitting the vibrations of said neck to said membrane, said means being under an initial tension directed against said membrane in opposition to said bridge.
4. The combination, in a banjo or like stringed musical instrument, of a rim, a membrane supported thereon, a neck projecting from the rim, strings stretched from the outer end of said neck to a point of securing on said rim opposite said neck, a bridge interposed between said strings and the membrane, means pivotally supporting said neck, intermediate its ends, from the rim, and means for transmitting the vibrations of said neck to said membrane, said means being under an initial tension directed against said membrane in opposition to said bridge, but not coinciding in location with the bridge.
5. The combination in a stringed musical instrument comprising a head including a sounding membrane, a neck projecting from said head, strings stretched across said membrane and secured to said head and to said neck outward of the head, and a bridge interposed between said membrane and said strings, of means forming a free pivotal support for said neck upon said head, and means operatively connecting said neck

with said membrane, to transmit to the membrane the vibrations initiated in said neck.

6. In a banjo or like stringed musical instrument, in combination, a head including a rim and a membrane stretched thereover, a neck extending through and pivotally supported in one side of the rim, strings stretched from the opposite side of the rim to the outer end of the neck, a short lever pivotally supported in the rim opposite the inner end of the neck, and links connecting an end of said short lever with the inner end of said neck, the opposite end of the lever contacting with the membrane.

7. In a banjo, a head including a rim, a neck, and a dowel post forming an extension thereof, and means pivotally supporting said neck in the rim, said dowel post and neck being otherwise disconnected from said rim and free to oscillate relative thereto.

8. The combination, in a stringed musical instrument including a rim and a sounding membrane supported thereon, of a neck projecting from the rim, means pivotally supporting the neck, intermediate its ends, from the rim for free vibration, strings under tension connected to the outer end of said neck and extending over the outer face of the membrane, said strings, when they are struck, causing said neck to vibrate transversely of the plane of the membrane, the inner end of said neck being operatively connected to said membrane to transmit its vibrations directly to the inner face thereof.

9. The combination, in a stringed musical instrument including a rim and a sounding membrane supported thereon, of a neck projecting from the rim, strings extending from the neck over the outer face of the membrane to a tail piece, a bridge interposed between the strings and the outer face of the membrane, a lever supported adjacent the inner face of the membrane, and bearing thereupon, and means connecting said lever to the neck to receive vibrations therefrom for transmission to the membrane.

Signed at Bellingham, Washington, this 2nd day of October, 1926.

CHARLES H. MERRITT.
